His Attorney.

UNITED STATES PATENT OFFICE.

CHARLES M. MARTIN, OF BOSTON, MASSACHUSETTS.

DESIGN FOR A BOX-COVER.

SPECIFICATION forming part of Design No. 30,476, dated April 4, 1899.

Application filed December 30, 1898. Serial No. 700,775. Term of patent 7 years.

To all whom it may concern:

Be it known that I, CHARLES M. MARTIN, a citizen of the United States, residing at Boston, in the county of Suffolk and State of Massachusetts, have invented and produced a new and original Design for a Box-Cover, of which the following is a full, clear, and exact description.

Referring to the drawings forming part of this specification, Figure 1 is a perspective view from beneath of the cover embodying my new design. Fig. 2 is a bottom view of the same, and Fig. 3 is an end view thereof.

As shown, the leading or material feature of my design consists of the flanges *a*, formed at the upper edges of the sides *A*, between which extends the part comprising the cover proper, *A'*. The sides *A* are narrower than the part *A'*, but are of equal width with respect one to the other. The flanges *a*, although

narrow, are parallel with the part *A'* and project toward each other. The ends of said flanges are rounded with a gentle curve, as shown more particularly in Fig. 2 at *a'*.

This cover being formed from metal can be 25 chased, engraved, or otherwise suitably ornamented.

Having described my invention, what I claim as new, and desire to secure by Letters Patent, is—

The design for a box-cover, as herein shown and described.

In testimony that I claim the foregoing invention I have hereunto set my hand this 22d day of December, 1898.

CHARLES M. MARTIN.
